UNITED STATES PATENT OFFICE.

THOMAS C. WHITEHEAD, OF DETROIT, MICHIGAN.

PUMP.

Application filed July 23, 1923. Serial No. 653,232.

The invention relates to pumps, being more particularly designed for use as a gas compressor, and the invention consists in the construction as hereinafter set forth.

5 In the drawings:

Figure 1 is a cross-section through the pump taken on the line 1—1 of Figure 3;

Figure 2 is a bottom plan view of the head looking from below upward;

10 Figure 3 is a section taken on the line 3—3 of Figure 1;

Figures 4 and 5 are plan views of the valve plates.

One of the objects of the invention is to 15 obtain a construction in which the seating and unseating of the valves is substantially noiseless, and a further object is to obtain a simple construction of valve. This I have accomplished by forming the valves of resilient 20 normally flat wafer-like strips covering the ports and which, under pressure, are slightly bowed to provide clearance between the same and the seat. The ports for the valves are preferably formed in one or more 25 plates interposed between the cylinders and the head and clearance for the bowing of the valves is provided by segmental recesses in the member above the seat.

In detail, A is the cylinder block and B 30 a detachable head therefor, which is preferably provided with inlet and outlet passages controlled or variably restricted by the shut-off valves C and D. As shown these valves have conical heads C' and D' engageable with suitable seats C'' and D'' and have upstanding stems C² and D² threadedly engaging bushings C³ and D³ carried by the head B. These inlet and outlet passages communicate with longitudinally extending 35 chambers E and F which are arranged upon opposite sides of the common central plane of the cylinders and extend the length of the series. Between the head B and cylinder block A are arranged one or more plates G, 40 which form seats for the valves. Preferably I employ two of such plates, which are duplicates but oppositely arranged. Thus as shown in Figures 3 and 4, the plate G has a series of segmental recesses H formed on 45 its lower side upon one side of the common central plane of the cylinders, and, as shown in Figure 5, the plate G' has a series of segmental recesses H' in its upper face on the 50 opposite side of the common central plane of the cylinders. The plate G is further provided with pairs of ports I, I' passing

through the plate in registration with each of the recesses H and with ports J on the opposite side of the central plane, which register centrally with the recesses H' of the 60 lower plate G'. The plate G' is provided with corresponding ports I, I' and J. K are strips of thin metal which are arranged in the recesses H and H', preferably extending beyond the segmental portions into extensions of said recesses. This permits each of the strips K to lie flush with the face of the adjacent plate, the strips in the recesses H' being adjacent to plate G and the strips in the recesses H adjacent to the plate G'. 70 The two plates may then be placed in registration and secured to each other by suitable means, such as the end lugs L and L', which are bolted to each other.

With the construction as described the 75 pair of plates G and G' is clamped between the head B and the cylinder block A and will function as follows: Normally all of the strips K are flat and cover the ports J of the adjacent plates. Thus whenever gaseous 80 pressure is exerted against a strip towards the plate having the registering port J, said strip will seal the port or close the valve. On the other hand, any gaseous pressure exerted through the port against the registering strip will bow such strip into the segmental recess, providing clearance therefor, 85 which will open the passage. In this manner the suction stroke of each piston will draw in gas from the passage E and through 90 the ports I, I' past the valve K and through the port J into the cylinder. During this stroke the outlet passage F is out of communication with the cylinders by the seating of the valves K. Upon the reverse stroke the 95 outlet valves will open and the inlet valves will be seated, but this movement is accomplished without noise, inasmuch as some portion of each strip K is always in contact with the adjacent plates G or G'. 100

What I claim as my invention is:

1. In a pump, the combination with a block having a plurality of cylinders therein, of a head, a pair of duplicate reversely arranged plates clamped between said head 105 and block, each plate having a series of segmental recesses opposite each cylinder and on one side of the common central plane of said cylinders, and a series of ports registering with said cylinders on the opposite 110 side of said common central plane, the ports of one plate also registering with the recesses

of the other plate, and strips of resilient material within said recesses normally lying flat to seat about the port in the adjacent plate but capable of bowing away from said seat into said segmental recess upon reversal of pressure.

2. In a pump, the combination with a plurality of cylinders and a common head for said cylinders, said head having an inlet and an outlet passage, of a pair of valves associated with each cylinder, controlling the inflow and outflow therefrom and each automatically responsive to pressure variations in the corresponding cylinder, and a pair of shut-off valves mounted in said head and controlling said inlet and outlet passages.

3. In a pump, the combination with a plurality of cylinders and a common head for said cylinders, of a pair of ported plates clamped between said head and cylinders, one of said plates having intake ports for the respective cylinders and the other plate having corresponding outlet ports, each of said plates being formed with recesses in its face adjoining the other plate, respectively in communication with the ports of the other plate, and leaf spring valves within said recesses controlling said ports and automatically responsive to pressure variations within the cylinders corresponding to said ports, said head having passages opening in its face adjoining said plates, connecting said intake ports and connecting said outlet ports.

4. In a pump, the combination with a cylinder, and a head therefor, of complementary plates between said cylinder and head having openings therein, the opposed faces of said plates having segmental recesses in com-

munication with said openings, and wafer valves in said recesses flush with the opposed faces of said plates controlling the flow of gases through said openings, the openings and recesses in one plate being offset with respect to the recesses and openings in the other plate whereby the opposed faces of said plates will serve as abutments for said valves.

5. In a pump, the combination with a cylinder, and a head therefor having spaced inlet and outlet gas passages, of plates between said cylinder and head having openings therein, the opposed faces of said plates having segmental recesses crossing said openings, and wafer valves in the recesses in the respective plates controlling the flow of gases through said openings, the openings in one plate communicating with the inlet passage in the head, and the openings in the other plate communicating with the outlet passage in the head, said plates being separable for the replacement and repair of said valves.

6. In a pump, the combination with a cylinder, and a head therefor having spaced inlet and outlet gas passages, of interchangeable plates between said head and cylinder having gas openings therein, the opposed faces of said plates having segmental recesses crossing said openings, and wafer valves in the recesses in the respective plates for controlling the flow of gases through said openings, the arrangement of openings and recesses in said plates being such with respect to the passages in said head that the valves in one plate will remain seated while the valves in the other plate are unseated.

In testimony whereof I affix my signature.
THOMAS C. WHITEHEAD.
